HUBERT W. MORGAN, OF WESTFIELD, MASSACHUSETTS, ASSIGNOR TO H. W. ELY, S. C. CARPENTER, ERASTUS COLLINS, J. S. CLARK, W. F. JOHNSON, DEXTER AVERY, AND H. W. MORGAN, ALL OF SAME PLACE.

CASKET OR COFFIN HANDLE.

SPECIFICATION forming part of Letters Patent No. 234,320, dated November 9, 1880.
Application filed August 25, 1880. (No model.)

To all whom it may concern:

Be it known that I, HUBERT W. MORGAN, of Westfield, county of Hampden, State of Massachusetts, have invented an Improvement 5 in Casket or Coffin Handles, of which the following description, in connection with the accompanying drawings, is a specification.

This invention relates to casket or coffin handles, and has for its object the production 10 of a novel class or kind of such trimmings as a new article of manufacture.

Until a quite recent period it has been customary to manufacture caskets of hard wood, such as mahogany, walnut, and cherry, the 15 better class of caskets being rubbed and finished to present a polished surface. Other caskets of wood have been finished with wood veneers polished, and more recently caskets have been made more or less of metal, and 20 also of vitreous or other substances which will not rot or perish as quickly as wood.

To avoid polishing the solid wood or veneers, which requires considerable time and is an expensive operation, caskets of hard and other 25 woods and of metal have been covered with a textile covering, such as woolen cloth, velvet, and silk, the colors being black or white. The handles applied to these textile-covered black-surfaced caskets have been made of silver, 30 metal silver-plated, German silver, and of white metal, all more or less burnished and having bright surfaces. This class of handles employed on black or white cloth-covered caskets are considered objectionable, as affording a too 35 great contrast, and if silver handles are used they are quite expensive.

The object of my invention is to produce strong, serviceable, neat, and desirable textile-covered casket-handles.

40 I have found by experiment that I may, by means of a plaiting or braiding machine or by a circular loom, cover a casket-handle with a seamless textile cover, presenting a neat appearance, and showing but little, if any, metal, 45 and the surface of the article so produced may be made to resemble lusterless black cloth, or velvet, or silk, according to the material selected for the textile cover made in accordance

with my invention. My invention herein to be claimed is therefore a casket-handle having 50 a seamless textile covering, the same being and constituting a new article of manufacture.

Figure 1 represents one form of casket-handle; Fig. 2, another form of handle made in accordance with my invention, and Fig. 3 a 55 section taken along Fig. 1.

The attaching-plates *a*, to receive screws by which to secure the handles or side bars to the casket, are composed of metal, as are also the socket parts *b*, that receive the hand-pieces 60 *c*, the said socket parts being pivoted or otherwise secured to the said plates in any usual way.

The hand-piece *c* will be composed of a rigid core-piece of wood or metal or of metal pipe, 65 2, having upon and surrounding it a tubular seamless textile cover, 3, fabricated upon the core-piece by means of an ordinary braiding or plaiting machine, such as now employed in whip-making or cord-covering.

To finish the end of the handles I cover 70 acorn-shaped or conical pieces of wood 4 with a seamless textile cover, 5, in the manner just described, the said pieces 4 and covers constituting end pieces. These end pieces have turned 75 or other stems 6, to enter sockets in the core-piece 2, and between the ends of the covered core-piece and end pieces I shall preferably apply socketed washers *d*; of metal, having a dark or light surface or edge, as may be desired, or wood, india-rubber, or leather; or, if desired, I may also cover the washers with a textile cover. The end pieces are further finished at their outer ends by means of tips *e*, of 80 metal or wood, the latter being textile-covered, 85 if desired.

In the drawings I have omitted the textile covering for the washers and tips.

The core for the hand-piece may be of greater or less length, according to the distance it is 90 desired that it shall extend along the side of the casket, and it may be embraced or held at suitable distances by suitable socket parts, *b*.

Caskets for children will have handles covered with a white textile covering.

I can produce a surface to resemble woolen

cloth by first covering the core with cotton thread and then flocking the tubular cotton covering with a woolen flock. This I prefer to do because of its cheapness. I can also, if desired, employ threads having cotton cores or centers and coated or covered with wool or silk, such class of threads being common. Threads entirely of wool are too elastic to be employed in braiding-machines.

10 In another application I shall describe and claim casket-trimmings having a flocked surface, the flock being deposited on wood or metal, or both.

Hand-pieces provided with textile covers afford a better surface for the hands of the bearers—a surface on which the hand or glove will not slip as easily as on metal; and my improved handle may also be made of larger di-

ameter and of less weight as compared with silver or plated handles.

I am aware that it is not new to cover whips, and also cotton and hempen cords, with a seam-
less braided cover.

I claim—

As an improved article of manufacture, a 25 casket or coffin handle having a rigid core or hand-piece provided with a tubular seamless textile covering, all substantially as described.

In testimony whereof I have signed my name to this specification in the presence of two sub- 30 scribing witnesses.

HUBERT W. MORGAN.
